Des. 189,506
Patented Dec. 27, 1960

189,506

PORTABLE CARRIER FOR GAS TANKS OR THE LIKE

Frank C. Pooch, Jr., Rte. 1, Box 350P, Stevensville, Mich.

Filed Feb. 2, 1960, Ser. No. 59,234

Term of patent 14 years

(Cl. D58—5)

Fig. 1.

Fig. 2.

Fig. 3.

I claim:

The ornamental design for a portable carrier for gas tanks or the like, as shown.
